SWIMMING POOL COPING

Robert Donald Robb, 1942 Marconi Ave.,
Sacramento, Calif.

Filed Nov. 6, 1962, Ser. No. 72,395

Term of patent 14 years

(Cl. D13—1)

FIG. 1.

FIG. 2.

FIG. 4.

FIG. 3.

FIG. 1 is a front perspective view, to a reduced scale, showing my new swimming pool coping design;

FIG. 2 is a top plan view;

FIG. 3 is a side elevational view; and

FIG. 4 is a front elevational view.

I claim:

The ornamental design for a swimming pool coping, as shown.
